UNITED STATES PATENT OFFICE

90,713

DESIGN FOR A TEA CART

Percival Goodman, New York, N. Y., assignor to
The McKay Company, Pittsburgh, Pa., a corporation of Pennsylvania

Application July 12, 1933. Serial No. 48,692

Term of patent 7 years

To whom it may concern:

Be it known that I, PERCIVAL GOODMAN, a citizen of the United States, residing at New York city, in the county of New York, State of New York, have invented a new, original, and ornamental Design for a Tea Cart, of which the following is a specification, reference being had to the accompanying drawing, forming a part hereof.

Figure 1 is a perspective view of a tea cart embodying my new design, and Fig. 2 is a side view of the tea cart.

I claim:

The ornamental design for a tea cart, as shown.

PERCIVAL GOODMAN.
